PETTICOAT

Arthur Immerman, Harrison, N. Y.

Application September 22, 1954, Serial No. 32,389

Term of patent 14 years

(Cl. D3—26)

FIG. 1.

FIG. 2.

To all whom it may concern:

Be it known that I, Arthur Immerman, a citizen of the United States, residing in Harrison, in the county of Westchester and State of New York, have invented a new, original, and ornamental Design for a Petticoat, of which the following is a specification, reference being had to the accompanying drawings, forming part thereof.

Fig. 1 is a front view of the petticoat.

Fig. 2 is a perspective view of the petticoat shown in Fig. 1 in wearing position.

The back presents substantially the same appearance as the front.

I claim:

The ornamental design for a petticoat, as shown and described.
